UNITED STATES PATENT OFFICE.

SYDNEY PAUL, OF LIMA, OHIO, ASSIGNOR TO SUPERIOR MOTOR COACH BODY CO., OF LIMA, OHIO, A CORPORATION OF OHIO.

CHAIR SEAT.

Application filed January 31, 1925. Serial No. 5,933.

The object of this present invention, briefly stated, is to provide a chair seat of new and novel construction, which is light in weight, strong and durable in construction, 5 attractive in appearance, and adapted to give a maximum of comfort to the user thereof.

More specifically stated, my object is to provide a chair-seat in which the body or frame is made of a single piece of laminated 10 material; in which the bottom frame of the cushion is in the nature of an endless hoop made of a single section of laminated material; and the novel means by which the cushion is removably and resiliently mounted 15 in the body or frame.

Other minor objects and particular features of the invention will be suggested in the course of the following description, and that which is new will be correlated in the 20 appended claim.

The preferred means for carrying out the principles of my invention in a practical manner is shown in the accompanying drawings, in which,—Figure 1 is a plan view 25 of the base, with the cushion removed. Figure 2 is a vertical cross section of the body taken on the line 2—2 of Fig. 1, also showing the cushion in place and as taken in cross section. Figure 3 is a bottom plan 30 of the cushion member of the seat. Figure 4 is a perspective enlarged detail view of one of the supporting brackets or hangers. Figure 5 is a detail view showing a cross section of the cushion frame.

Similar indices denote like parts throughout the several views.

In order that the construction, the operation, and the several advantages of this invention may be more fully understood and appreciated I will now take up a detailed description thereof, in which I will set forth the same as comprehensively as I may.

The main portion comprises the base 1 which is substantially in the nature of a 15 hollow square with rounded corners, and it is built up of a plurality of layers of wood veneer stock, with the layers glued together, and it is preferably formed of one continuous length of material wound about a form 20 to the shape shown.

Each of the members 2, 3, 4 and 5 forms a leg and foot, the latter two members continue upward forming the posts for the back, but with these members 2, 3, 4 and 5 25 this invention is not concerned.

Secured to the inner face of the base 1, and located at each corner thereof, and extending therebelow, are the four brackets 6, 7, 8 and 9. Said brackets are all identical with each other, each having a vertical portion and a horizontal portion, which portions are at right-angles to each other, and said portions are reinforced and strengthened by a rib, as the respective ribs *a*, *b*, *c* and *d*. 60

The outer end portion of each of the horizontal parts of said brackets is enlarged forming a circular face or plate *e*, *f*, *g* and *h*, respectively. Said brackets are each secured to the inner face of the base 1 by a 70 plurality of screws 20, which are inserted through apertures 19 in the vertical portions of said brackets.

Formed integral and concentric with each face *e*, *f*, *g* and *h* are the upwardly extending cone-like lugs 10, 11, 12 and 13. 75

Numerals 14, 15, 16 and 17 denote the respective helical springs, the lower ends of which fit around the respective lugs 10, 11, 12 and 13, where they are secured each by 80 a cotter-pin 18, with the lower ends of said springs resting on their respective faces *e*, *f*, *g* and *h*.

Each two of said springs is connected at their upper portions by a rod or wire, 23, 85 24, 25 and 26, although in some instances this may be dispensed with.

Reinforcements 21 and 22 are secured to the outer faces of the two sides of the base 1, and they extend between the respective front and rear legs, substantially as shown. 90

We now have the parts of the body of the seat assembled as in Fig. 1, ready to receive the removable cushion in connection therewith. 95

The cushion, shown in Figs. 2 and 3, comprises a substantially square rim 27, with rounded corners, corresponding in shape with the base 1, but of less horizontal dimensions, and it is of such dimensions as to 100 fit loosely inside the base 1, and it is adapted to rest on the upper ends of the springs 14, 15, 16 and 17.

Stretched across the inside of the rim 27 and secured thereto are the various strips of 105 webbing 28, or other material. Resting on the webbing are a plurality of coil springs 29, and covering said springs and in contact with the upper ends thereof is the padding 30. Covering said padding, and extending 110

downward to enclose the springs 29, and secured to the rim 27, is the upholstering material 31.

A plurality of lugs 32 are provided, which 5 lugs correspond with the lugs 10, 11, 12 and 13, and they extend down from the underside of the rim 27 and fit in the upper ends of the springs 14, 15, 16 and 17, substantially as shown in Fig. 2.

From the above it will be seen that I provide a chair seat construction wherein a person seated on the cushion will not only be supported by the springs 29 as in the usual manner, but that the entire cushion and the 15 load will be supported by the springs 14, 15, 16 and 17, thereby providing a two-fold resiliency for the person seated on the cushion.

This construction also provides means 20 whereby the cushion may be instantly removed by simply lifting it upward, after which the interior of the base-rim, and the parts attached thereto, may be easily cleaned, as well as the cushion.

Having now fully shown and described 25 my invention, what I claim and desire to secure by Letters Patent of the United States, is—

A chair seat including a base frame, legs 30 for supporting the frame, a bracket secured to the inner face of each corner portion of

the frame, each of said brackets including a vertical portion which contacts with the inner face of the base and to which it is secured, a horizontal portion extending inward from the lower end of the vertical portion and integral therewith, a rib located in the angle formed by the vertical portion and the horizontal portion, the outer part of each horizontal member being enlarged forming a circular plate, and a cone-shaped lug integral with and extending up from the face of said plate with an aperture formed horizontally through said cone; a coil spring having its lower end fitting around said cone 45 and resting on said plate, a pin inserted through said aperture and extending out at each end with the ends located between coils of its spring; rods connecting the upper ends of said springs and spacing them apart, a cushion member adapted to fit inside said base, a plurality of coil springs located vertically in the cushion, said cushion being adapted to rest on the upper ends of the first mentioned springs, the two sets of 50 55 springs being adapted to operate synchronously to support a person seated on the cushion.

In testimony whereof I have hereunto subscribed my name.

SYDNEY PAUL
